(57) **CLAIM**

We claim the ornamental design for a charger for an electric skin brush, as shown and described.

DESCRIPTION

FIG. 1 is an isometric view of the charger for an electric skin brush showing our new design;

FIG. 2 is a left side elevational view thereof;

FIG. 3 is a right side elevational view thereof;

FIG. 4 is a rear elevational view thereof;

FIG. 5 is a front elevational view thereof;

FIG. 6 is a top plan view thereof; and,

FIG. 7 is a bottom plan view thereof.
